UNITED STATES PATENT OFFICE.

BRADLEY ELI PICKETT, OF YANKTON, SOUTH DAKOTA.

NECK-PAD.

1,272,084.

Specification of Letters Patent. Patented July 9, 1918.

Application filed August 30, 1917. Serial No. 188,985.

To all whom it may concern:

Be it known that I, BRADLEY ELI PICKETT, a citizen of the United States, and a resident of Yankton, in the county of Yankton and State of South Dakota, have invented 5 new and useful Improvements in Neck-Pads, of which the following is a specification.

My invention is an improvement in neck pads, and has for its object to provide a pad 10 of the character specified, adapted to be arranged between the collar and the hames, for permitting free movement of the hames without rubbing the neck of the draft animal.

15 In the drawings:

Figure 1 is a section on the line 1—1 of Fig. 2, looking in the direction of the arrows adjacent to the line;

Fig. 2 is a top plan view;

20 Fig. 3 is a similar view showing the parts in another position;

Fig. 4 is a section on the line 4—4 of Fig. 3, looking in the direction of the arrows adjacent the line;

25 Fig. 5 is a side view showing a portion of the hames and the connection between the same.

In the present embodiment of the invention, the pad 1, which connects the hames, 30 is provided with a yoke shaped member comprising a body 2 which is secured to the pad and upstanding arms 3, and the said arms carry a shaft or bolt 4. A bearing sleeve 5 is mounted on the shaft or 35 bolt, and this bearing sleeve has an upstanding pin 6 to which is riveted a curved bar 7. The connecting strap 8^a between the hames 9 rests upon this bar 7, and the said bar has upstanding lugs 8 at its center, 40 preventing displacement of the strap. The bar also has clips 10 at its end which embrace the strap, to hold it in place, and the ends of the strap engage the usual loops 11 on the hames.

45 In practice, the shaft 4 is a bolt which extends through the arms 3 of the yoke and is engaged by a nut 12 to hold it in place. The pad 1 is the ordinary pad used at the top of the collar where the ends of the collar are connected, and the said pad consists, 50 as usual, of a leather portion and a metallic

portion, the metallic portion being arched and secured to the leather portion as shown in Fig. 1, and the pad conforms to the shape of the top of the collar.

55 In use, the bar 7 may be rocked upon the shaft 4 or may be moved longitudinally of the said shaft, as indicated in dotted lines in Fig. 1, or the said bar may swing laterally with respect to the pad, as indicated in dotted lines in Fig. 2. In fact, the connection between the pad and the bar is a universal joint connection, permitting movement in either direction.

65 I claim:

1. In a device of the character specified, the combination with the neck pad, of a yoke shaped member comprising a body secured to the pad and upstanding arms, a shaft carried by the arms, a bar having a bearing sleeve engaging the shaft, and a leather connection for the hame supported by the bar, said bearing sleeve being movable longitudinally of the shaft, and the bar being pivoted to the sleeve to permit lateral movement of the bar with respect to the sleeve.

2. A neck pad adapted to be arranged between the meeting ends of a collar on the horse's neck, a rod held transversely of the pad above the same, a sleeve journaled on the rod and movable longitudinally thereof, and a curved bar having means for engaging the hame connecting strap, journaled on the rod and movable longitudinally thereof.

3. A neck pad having a rod arranged transversely thereof above the same, and a rigid bar having means for engaging the hames connecting strap mounted to slide and to rock on the rod and to swing laterally with respect thereto.

4. A neck pad, and a rigid bar having means for engaging the hames connecting strap connected with the pad at the top thereof to rock on the pad to swing laterally with respect thereto and to move transversely of the pad.

95 BRADLEY ELI PICKETT.
